ATTORNEY

UNITED STATES PATENT OFFICE

FRANK W. ANDREWS, OF FORT WAYNE, INDIANA, ASSIGNOR, BY MESNE ASSIGNMENTS,
TO APEX ELECTRICAL MANUFACTURING COMPANY, OF CLEVELAND, OHIO, A COR-
PORATION OF OHIO

MEANS FOR LUBRICATING REFRIGERATION SYSTEMS

Application filed March 19, 1928. Serial No. 262,815.

My invention relates to refrigeration systems and particularly to those in which a sufficient quantity of lubricant is mixed with refrigerant when the system is charged and sealed, to effectually lubricate all moving parts where friction would cause wear.

Considerable difficulty has been experienced in small units, such as those adapted for household use, by the accumulation of a large amount of lubricant in some part of the system as the liquid refrigerant receiver of a dry system, and because such quantity of lubricant remains in the receiver in that case, an insufficient amount is carried over to the compressor and other working parts to keep them properly lubricated.

The principal object of my invention is to provide a method of and means for keeping the lubricant in the system circulating therethrough, that is, as fast as it comes over from the outlet side of the compressor to the liquid receiver or other part of the system where it becomes trapped, to pass it directly through said receiver instead of allowing it to accumulate and remain therein.

My invention as applied to a refrigeration system of the dry type is illustrated in the accompanying drawings in which:—

Figure 1 is a side elevation of a liquid refrigerant receiver, with parts broken away and in section to show the invention in its preferred form, with parts of the tubes broken away and in axial section, and

Fig. 2 is a similar view of one end of the receiver, broken and in section to expose to view an alternative form of my invention, also with tube broken and in section. The surrounding valve mechanism is broken away.

Referring now to the drawings and particularly to Fig. 1; 1 is the liquid refrigerant receiver, with liquid gas inlet pipe 2, liquid gas outlet pipe 3, controlled by a suitable valve 4 and having outlet tube 5 through which liquid gas flows to the cooling unit (not shown.)

An open ended supply tube 6 terminates at its lower end below the minimum normal level of liquid gas in the receiver 1 and preferably near the bottom thereof. Liquid gas passes upwardly from the receiver 1 through

supply tube 6, valve 4 and outlet tube 5, but will not of itself carry the oil O which accumulates on top of the body of liquid refrigerant R freely enough to keep all the moving parts (not shown) of the apparatus lubricated, and a considerable quantity of the oil accumulates in the liquid refrigerant receiver.

To prevent this by causing the oil to pass over to the cooling unit with the liquid refrigerant a tubular wick holder 7, piercing the side of the supply tube 6 and united therewith, extends outwardly and downwardly, its outer end preferably resting on the bottom of the liquid refrigerant receiver. This tube 7 is preferably provided with a slot on the top side or otherwise provided with one or more openings extending through its wall and filled with a suitable fibrous wick W, or other means for raising the oil by capillary attraction, and preferably this wick protrudes out of said lower end so that the free ends of said fibers may contact with the body of oil O as well as a portion of the encased wick at all levels of the oil.

In the form of the device shown in Fig. 2, there is no laterally extending tube 7, but the supply tube 6 there designated as 9, has a partition 10 extending nearly but not quite to the top of said tube, a wick W is put into one chamber of the tube, and the wall of that chamber is provided with a slot 11 or other openings to bring the body of oil in the liquid receiver 1 into contact with the wick at all levels.

The wick W is soaked with the lubricant before the apparatus is charged with refrigerant. The oil rises on the wick and particles thereof are delivered from the upper end of the wick from time to time or constantly into the rising body of liquid refrigerant in the supply tube 6, and are carried over with said refrigerant to accomplish the purpose of the invention.

While I have shown and described the best forms of the invention known to me, I do not wish to be limited to these forms, but claim any apparatus using a wick or other capillary means to carry over the lubricant from any receptacle in the system where it becomes

pocketed as within the scope of my invention.

I claim as my invention and desire to secure by Letters Patent of the United States:

- 5 1. In a refrigeration system through which lubricant is circulated with refrigerant; a liquid receiver, an outlet tube from an upper part of said receiver extending downwardly and terminating in said receiver below the normal level of liquid therein, and wick means 10 for conveying lubricant in said receiver into said tube, said tube connected into the next point of the system through which refrigerant normally passes in the cycle of its circulation.
- 15 2. In a refrigeration system through which lubricant is circulated with refrigerant; a liquid receiver, an outlet tube from said liquid receiver extending downwardly from and above and terminating in said receiver below 20 the normal level of liquid therein and a wick extending from within said outlet tube into the body of lubricant in said receiver, said tube connected into the next point of the system through which refrigerant normally 25 passes in the cycle of its circulation.

3. In a refrigeration system through which lubricant is circulated with refrigerant; a liquid receiver, an open ended outlet tube whose upper end pierces and is sealed to the 30 top of said receiver and extends downwardly terminating in said receiver below the normal level of liquid therein, and a wick whose upper end is within said tube, and which passes through the body of lubricant in said 35 receiver and contacts therewith, said tube connected into the next point of the system through which refrigerant normally passes in the cycle of its circulation.

4. In a refrigeration system having a compressor through which system lubricant circulates with refrigerant, means for conveying lubricant by capillary attraction to the next portion of the system through which refrigerant normally passes in the cycle of 45 its circulation from any point where it would otherwise become trapped.

5. In a refrigeration system having a compressor through which system lubricant circulates with refrigerant, wick means for 50 forwarding lubricant to the next portion of the system through which refrigerant normally passes in the cycle of its circulation from any point where it would otherwise become trapped.

6. In a refrigeration system through which lubricant is circulated with refrigerant; a receptacle in which lubricant becomes pocketed, an outlet above the liquid level in said 55 receptacle, a connection from said outlet to the next portion of the system through which refrigerant normally passes in the cycle of its circulation, and capillary means extending from the accumulated lubricant in said 60 receptacle to a place contiguous to said outlet

in the path of refrigerant flowing therethrough.

7. In a refrigeration system through which lubricant is circulated with refrigerant; a receptacle in which lubricant becomes pocketed, an outlet above the liquid level in said receptacle a connection from said outlet to the next portion of the system through which refrigerant normally passes in the cycle of its circulation, and wick means extending 75 from a place contiguous to said outlet and in the path of refrigerant flowing therethrough downwardly into the body of accumulated lubricant.

8. In a refrigeration system through which lubricant is circulated with refrigerant; a receptacle in which lubricant becomes pocketed, an outlet above the liquid level in said receptacle, a connection from said outlet to the next portion of the system through which refrigerant normally passes in the cycle of its circulation, a perforated tube extending downwardly from a place contiguous to said outlet and in the path of refrigerant flowing therethrough to the body of lubricant in said 85 receptacle and a wick in said tube.

9. In a refrigeration system through which lubricant is circulated with refrigerant; a liquid receiver, an outlet tube connecting an upper part of said receiver with the next 95 portion of the system through which refrigerant normally passes in the cycle of its circulation, said tube extending downwardly and terminating in said receiver below the normal level of liquid therein, a branch tube 100 connected to an upper part of said outlet tube and extending downwardly into said receiver to the lubricant at any of its levels, a wick extending through said branch tube and terminating in said outlet tube and means for 105 permitting lubricant to pass through the wall of said branch tube.

10. In a refrigeration system through which lubricant is circulated with refrigerant; a liquid receiver, an outlet tube connecting an upper part of said receiver with the next portion of the system through which refrigerant normally passes in the cycle of its circulation, said tube extending downwardly and terminating in said receiver below the 110 normal level of liquid therein, a slotted branch tube connected to an upper part of said outlet tube and extending downwardly into said receiver through the lubricant at all of its levels, and a wick extending through said 115 branch tube and terminating in said outlet tube.

11. In a refrigeration system through which lubricant is circulated with lubricant; a liquid receiver, an outlet tube connecting an upper part of said receiver with the next portion of the system through which refrigerant normally passes in the cycle of its circulation, said tube extending downwardly and terminating in said receiver below the normal 125 130

level of liquid therein, a slotted branch tube connected to an upper part of said outlet tube and extending downwardly into said receiver through the lubricant at all of its levels, a wick extending through said branch tube and terminating in said outlet tube and extending out of the lower end of the branch tube so as to contact with the body of lubricant in the receiver.

In testimony whereof I have hereunto set
10 my hand.

FRANK W. ANDREWS.
